HYPODERMIC SYRINGE PACKAGE

Richard L. Panicci, Westfield, Mass., assignor to Pharma-seal Laboratories, Glendale, Calif., a corporation of California

Filed Nov. 16, 1966, Ser. No. 4,701

Term of patent 14 years

(Cl. D83—12)

FIG. 1.

FIG. 2.

FIG. 3.

FIG. 4.

FIG. 5.

FIG. 1 is a top plan view of a hypodermic syringe package, showing my new design;

FIG. 2 is a side elevation thereof;

FIG. 3 is a left end elevation thereof;

FIG. 4 is a right end elevation thereof; and

FIG. 5 is a perspective view thereof.

I claim:

The ornamental design for a hypodermic syringe package, as shown.
